(57) **CLAIM**

The ornamental design for a choke coil, as shown and described.

DESCRIPTION

FIG. 1 is a front elevational view of an ornamental design for a choke coil;

FIG. 2 is a rear elevational view of the choke coil of FIG. 1; FIG. 3 is a left side elevational view of the choke coil of FIG. 1;

FIG. 4 is a right side elevational view of the choke coil of FIG. 1;

FIG. 5 is a top plan view of the choke coil of FIG. 1;

FIG. 6 is a bottom plan view of the choke coil of FIG. 1; FIG. 7 is a perspective view of a front, bottom, and right side of the choke coil of FIG. 1; and,

FIG. 8 is a perspective view of a rear, top, and right side of the choke coil of FIG. 1.

The dashed broken lines show portions of the choke coil that form no part of the claimed design.
